Attorney.

UNITED STATES PATENT OFFICE.

CHARLES MUNZNER, OF CHICAGO, ILLINOIS, ASSIGNOR TO AMERICAN STOVE COMPANY,
OF ST. LOUIS, MISSOURI, A CORPORATION OF NEW JERSEY.

PERFORATED COMBUSTION-SECTION.

1,333,563.

Specification of Letters Patent.

Patented Mar. 9, 1920.

Application filed January 10, 1919. Serial No. 270,538.

To all whom it may concern:

Be it known that I, CHARLES MUNZNER, a citizen of the United States, residing at Chicago, in the county of Cook and State of Illinois, have invented certain new and useful Improvements in Perforated Combustion-Sections, of which the following is a specification, reference being had therein to the accompanying drawing.

10 This invention relates to improvements in perforated combustion sections for oil stoves, and the particular improvement pertains especially to the inner perforated tube of the combustion section.

15 This improvement relates to a well-known type of perforated combustion section for oil stoves, which comprises inner and outer parallel perforated combustion tubes, which have their lower ends seated at opposite

20 sides of the point where the vapor is generated, the generated vapor flowing upward between the combustion sections and air passing outward through the perforations of the inner section and inward through the

25 perforations of the outer section and mixing with the rising vapor, issuing between the upper ends between the inner and outer sections in a blue smokeless flame. In some types of burners utilizing the perforated

30 combustion section, the vapor is generated from a wick between the lower ends of the two tubes of the combustion section, and sometimes the vapor is generated in a trough which communicates between the

35 lower ends of the two tubes, the latter type of burner being commonly known as the "wickless" burner. My present improvement is adapted to be used with either the wick or wickless type of burner, and the

40 burner forms no part of my present invention.

Various forms of perforated combustion sections have been proposed for use in burners of the type to which my present

45 invention pertains, but in the practical and commercial type of combustion sections in use for a great many years, the inner and outer tubes have practically universally been made of sheet metal.

50 It is well-known to those skilled in this art that the inner combustion tube is subjected to intense heat during the operation of the burner and becomes red hot, and that

the temperature of the combustion section is lowest at their lowest ends and gradually increases to their upper ends. Owing to the intense heat to which the inner tube is subjected, it is much shorter lived than the outer tube, and owing to the unequal temperature of the inner tube throughout its length, its expansion and contraction causes it to bulge and become uneven which unevenness seriously interferes with the perfect combustion of the burner. Various constructions of inner tubes have been proposed to overcome the foregoing frailties of the sheet-metal inner tube, but so far as I am aware, none of them have been adopted to any serious extent and the plain sheet-metal inner perforated tube has been practically universally used in the commercial burners of this type.

The primary object of my invention is to construct the inner tube of cast-iron, and a further feature is the particular construction of the inner tube of cast iron, whereby the foregoing cited frailties and defects of sheet-metal inner tubes are overcome.

A further object of my present improvement is an improved combustion section made up of an inner cast-iron tube and an outer sheet-metal tube.

In the accompanying drawings:

Figure 1 is a perspective view of my improved inner combustion tube.

Fig. 2 is a vertical transverse central sectional view of a combustion section embodying my present improvement.

Fig. 3 is a fragmentary interior perspective view of one of the cast-iron rings forming part of my improved combustion tube.

Fig. 4 is a fragmentary exterior perspective view of one of the cast-iron rings used in my improved combustion tube.

The inner combustion section 1, of my improvement, is made up of a plurality of separate intermediate rings 2 and 3, a lower ring 4, and a top disk 5. All of these rings and top are composed of cast-iron. The rings 2 are narrower than the rings 3 and 4, as shown. The rings 2 are provided with inner off-set flange members 6 at one edge and the outer off-set flange 7, at their opposite edges. One edge of these rings is provided with a plurality of vertically arranged

notches 8, which extend thereinto to form passages extending from the inside to the outside of the tube 1.

The wider ring 3 is also provided with 5 the flanges 6 and 7 and with the notches 8 in one edge thereof, and in addition this wider ring has deeper and larger notches 9, through which metal rods 10 pass. These rods may pass also through the outer combustion tube 11 and the surrounding hood 12 serving to unite the inner and outer combustion sections and the hood in their proper spaced relation, as shown in Fig. 2, or the hood may be separately supported, 15 but this forms no part of my present invention.

The lower ring 4, has a flange 6^a at its upper edge, but has no flange at its lower edge 13. For illustrative purposes, the 20 combustion section is here shown in communication with the wick tube form of burner, and the lower ends of the inner and outer tubes 1 and 11 are seated between the flanged upper ends 14 of the wick tubes 25 15, as clearly shown in Fig. 2.

The several parts comprising the inner cast-iron combustion section 1, are held clamped together by a plurality of longitudinally extending screw-threaded rods 16, 30 here shown to be three in number. These rods pass through lugs 17, extending inward from the lower ring 4 and are screw-threaded into the top plate 5, as clearly shown, and by means of which the rings and top are firmly clamped together.

As is well known to those skilled in this art, the perforations in the combustion tubes, both inner and outer, are out of line, or, in other words are staggered as this is 40 found to be the most efficient arrangement to uniformly mixed air with the rising vapor between the inner and outer tubes. For the purpose of insuring the assembling of the rings 2, 3 and 4 in such positions that the 45 adjacent slots or passages 8 are out of line with each other, each of these rings is provided with a lug 18, and this lug enters one of the slots 8 of the adjacent ring. This lug 18 is located in a vertical line between the 50 slots 8, as clearly shown in Fig. 3, so that in assembling the rings, the lug 18 is obliged to enter one of the slots 8, and by reason of its location insures that the notches of the adjacent rings shall be out of line with each 55 other.

It is also well-known to those skilled in the art, that means is provided for lifting the combustion sections to permit access to the wick or wickless burner for lighting it, 60 and that the lifting means engages the inner combustion section, and that this is generally centrally arranged in the inner combustion section. To provide for the usual lifting rod one of the intermediate rings 2 is provided with an inwardly extending spider 19,

which carries a centrally upwardly projecting socket 20, adapted to receive the lifting rod. It is also well-known that the inner combustion tube is usually provided with one or more air deflecting diaphragms or 70 members, and these are provided in my improved construction by casting the desired number of diaphragms 21 integral with one or more of the rings 2.

Attention is directed to the fact that my 75 improved combustion section comprises an inner cast-iron tube and an outer sheet-metal tube. With this form of combustion section, the inner cast-iron tube which is subject to the severe heat will last longer 80 than a sheet-metal tube, thus producing a combustion section much longer lived than one composed wholly of sheet metal. In the ordinary sheet metal combustion section an inner tube is much shorter lived 85 than the outer tube, and when the inner tube becomes defective, it must be replaced by a new one, or a complete new combustion section provided.

It will be observed that the flange-members 6 constitute, in effect, a continuous flange, though, of course, the slots 8 cut up this flange into what might be termed flange members or a series of short flanges, while the flange 7, at the other edge is continuous. 95

I prefer to form the rings with flange members 6 extending all around, because it better serves to prevent the lateral passage of air between the edges of the rings and does not require an accurate fit of these 100 edges, and for the same reason I prefer to have the flange 7 extend all the way around the rings. However, it will be readily understood that by making a substantially good fit between the engaging edges of the rings, 105 the members 6 and the flange 7 need not extend throughout the peripheries of the rings, as shown, and just a sufficient number of flange members at both edges of the ring, for instance, four in number, would serve to 110 centralize the rings into tubular form, and the appended claims are to be considered as covering such modification.

For the purpose of cheapness, I prefer to make an inner tube of cast-iron, but it will 115 be understood it could be composed of any other suitable metal which would serve the purpose of durability, without departing from the spirit of my present improvement.

Having thus described my invention, what 120 I claim and desire to secure by Letters Patent is—

1. A perforated combustion section of the type described, having an inner cast-metal tube made up of a plurality of horizontally 125 arranged rings, each ring having its opposite edges provided with upwardly and downwardly extending flanges, one flange arranged at the inner side of the ring and the other flange at the outer side of the ring, 130

the rings arranged with their flanges overlapping, the overlapping flanges having registering transverse openings, for the purpose described.

5. 2. A perforated combustion section of the type described, having an inner cast-metal tube, composed of a plurality of horizontally arranged rings each having at the inner side of one edge a vertically arranged flange and at the outer side of the other edge a vertically arranged flange, whereby the rings are interlocked in tubular relation, one edge of the rings having transverse air-passages and longitudinally arranged clamping members for holding the rings in their assembled tubular relation.
10. 3. A perforated combustion section of the type described, having an inner cast-metal tube composed of a plurality of horizontally arranged rings having slots in one of their edges, and vertically arranged interlocking members for holding them in tubular form, one edge of the rings having a lug arranged out of vertical alinement with its 25 slots and adapted to engage one of the slots of an adjacent ring for the purpose de-

scribed, and longitudinally arranged clamping members for holding the rings in their tubular relation.

4. A perforated combustion section of the 30 type described, having an inner cast-metal tube composed of a plurality of horizontally arranged rings, each ring having transversely arranged air-passages, some of the rings having integral inwardly extending 35 air-deflecting diaphragms and longitudinally arranged means for clamping the rings in their tubular relation.

5. A perforated combustion section of the 40 type described, having an inner cast-metal tube composed of a plurality of horizontally arranged rings having transversely arranged air-passages, a top plate, the lower ring having inwardly extending lugs and longitudinally arranged clamping members 45 passing through lugs and into the top for holding the parts in their assembled relations.

In testimony whereof I hereunto affix my signature.

CHARLES MUNZNER.
